Pavane[57] **CLAIM**

The ornamental design for a furniture frame, as shown
and described.

DESCRIPTION

FIG. 1 is a side perspective view of a furniture frame
showing my new design and in which the frame is
shown in a first articulated position thereof;

FIG. 2 is a top plan view of the furniture frame of FIG.
1 in a second articulated position thereof;

FIG. 3 is a right side elevational view of the furniture
frame in its second articulated position, the left side
being a mirror image thereof;

FIG. 4 is a front elevational view of the furniture frame
in its second articulated position, the rear view being a
mirror image thereof; and,

FIG. 5 is a bottom plan view of the furniture frame in its
second articulated position.

FIG. 1

FIG. 2
